UNITED STATES PATENT OFFICE.

LOUIS M. MILLER, OF PHILADELPHIA, PENNSYLVANIA, ASSIGNOR OF ONE-HALF TO JAMES HOWARD LUMIS, OF WEST CHESTER, PENNSYLVANIA.

HANDLE FOR CYCLES.

SPECIFICATION forming part of Letters Patent No. 593,162, dated November 2, 1897.

Application filed August 28, 1896. Serial No. 604,157. (No model.)

To all whom it may concern:

Be it known that I, LOUIS M. MILLER, a citizen of the United States, residing at the city and county of Philadelphia and State of Pennsylvania, have invented certain new and useful Improvements in Handles for Cycles, &c., of which the following is a full, clear, and exact description, reference being had to the accompanying drawings, forming a part of this specification.

The object of this invention is to provide a pneumatic handle of simple and efficient construction for bicycles and analogous vehicles, whereby the usual jarring action upon the hands of the rider is materially reduced; and to this end the invention, as generally stated, consists in the provision of a shell or tube of rubber provided on its outer extremity with an air-valve and fitted to the end of the handle-bar, whereby the said shell or tube may be readily inflated, as will hereinafter appear.

In the drawings, Figure 1 is a perspective view of the handle as applied to the handle-bar of a cycle. Fig. 2 is a longitudinal section thereof. Fig. 3 is a transverse section, as on the line $x-x$ of Fig. 2.

A represents my improved handle, and B a handle-bar to which it is applied. The handle comprises an india-rubber tubular member which is snugly slipped upon the end of the handle-bar. Within the wall of this member is formed a circular series of longitudinal cells a , the inner ends of which are closed, as at a' , while their outer ends terminate in a common passage a^2 at the extremity of the handle-bar. The external portion of this cellular member extends outwardly beyond the handle-bar, as at a^3 , and is equipped with an air-valve of any approved pattern. In the present instance the valve comprises a screw-threaded shell c , provided on its inner end with a flange c' , which engages the inner side of an internal flange c^4 in the extension a^3 and is securely clamped thereagainst by means of a coacting washer c^2 and screw-nut c^3 on the shell. In this shell is fitted the valve c^4 , which normally seals the air-inlet port. Screwed on the outer end of the shell is a cap c^5 , on which is formed or secured a hood c^6 ,

that embraces and incloses the outer end extension of the tubular member and affords a shield therefor.

To inflate the handle, the cap, with its hood, is removed and the nipple of an air-pump of usual construction is applied to the valve-shell. Air is forced through the valve into the common passage a^2 , thence to the series of cells, thus inflating the outer portion of the handle and at the same time clamping the inner portion thereof tightly against the centrally-disposed handle-bar. This being done the pump is detached from the valve and the cap and hood are reapplied to the handle.

The exterior of the handle is preferably, though not essentially, swelled, and longitudinally fluted or corrugated, so as to afford a firm and convenient grasp for the hand.

I claim as my invention—

1. As a new article of manufacture, a pneumatic handle for bicycles, &c., the same comprising an elastic tubular member having formed therein a series of longitudinal radial cells the inner ends of which are closed while the outer ends terminate in a common passage, an air-valve on the outer extremity of said member having communication with said common passage, and a hood or shield embracing and protecting such extremity, whereby when air is injected into said common passage, by way of the valve, the outer portion of said member is expanded and the inner portion thereof is clamped upon the handle-bar to which the pneumatic handle is applied, substantially as described.

2. In a handle for cycles, &c., the combination, with an inflatable tubular member, of an air-valve on the outer extremity thereof, and a cap on said valve provided with a hood or shield that embraces and protects the end of such tubular member, substantially as described.

In testimony whereof I have hereunto affixed my signature in the presence of two subscribing witnesses.

LOUIS M. MILLER.
